(57) **CLAIM**

The ornamental design for a USB mobile flying insect trap, as shown and described.

DESCRIPTION

FIG. 1 is a front and top perspective view of a USB mobile flying insect trap design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom view thereof; and,

FIG. 9 is an enlarged view of the USB mobile flying insect trap taken from the circle part in FIG. 4.

The broken lines in the drawings depict portions of the USB mobile flying insect trap that form no part of the claimed design.
